ADOLPH K. MEINECKE AND ALFRED WILD, OF MILWAUKEE, WISCONSIN, ASSIGNORS
TO MEINECKE MFG. CO., OF MILWAUKEE, WISCONSIN, A CORPORATION OF WIS-
CONSIN.

CARRIAGE.

1,347,517.

Specification of Letters Patent.

Patented July 27, 1920.

Application filed December 1, 1917. Serial No. 204,814.

To all whom it may concern:

Be it known that we, ADOLPH K. MEINECKE and ALFRED WILD, citizens of the United States, and residents of Milwaukee, in the county of Milwaukee and State of Wisconsin, have invented new and useful Improvements in Carriages, of which the following is a description, reference being had to the accompanying drawings, which are a part of this specification.

Our invention has relation to improvements in baby carriages or vehicles.

The primary object of the invention is to provide an improved construction adapted to form the side panels, and the front and rear panels of the body, and also, where the carriage is equipped with a canopy, to form the side panels, and the top and back panels of said canopy, the construction and arrangement being such that the said panels may be constructed of an inexpensive material, such as veneer sheets capable of being previously woven on an ordinary loom.

With the above primary object, and other incidental objects, in view, the invention consists of the devices and parts, or the equivalents thereof, as hereinafter more fully set forth.

In the accompanying drawing:

30 Figure 1 is a perspective view of a baby carriage embodying our invention;

Fig. 2 is a cross-sectional view, on an enlarged scale, taken on the line 2—2 of Fig. 1, and looking in the direction of the arrows; and

Fig. 3 is a perspective view of the canopy. Referring to the drawings, the numeral 4 indicates the wheels, 5 the ordinary spring supporting frame, and 6 the handle of the 40 baby carriage.

The body of the carriage, comprising the side panels and the front and rear panels, is of peculiar and novel construction, and will now be described.

45 These panels consist of a woven fabric, the warp strands thereof consisting of sheets or strips 7 of inexpensive material, preferably veneer sheets, and the woof strands 8 consisting of light inexpensive material such as twisted paper cords, preferably of circular form in cross section. This woven material is shaped and cut to suit the particular design or style adopted for the body of the carriage. The edges of the different 55 panels are then inserted into metallic U-

shaped channels 9 firmly clenched to the woven fabric by bending the flanges of the U-shaped channels toward each other. The U-shaped channels, therefore, not only form part of the frames, but also actually form 60 and hold the woven material tight like a drum. Screws are turned through the lower U-shaped channels and enter the edges of the wooden bottom of the carriage, whereby the necessity of employing upright wooden 65 frames is avoided.

Frequently, it is desirable to provide the top edges of the panels with an ornamental border. The U-shaped channels 9 form a convenient means for attaching such ornamental border, and for this purpose the tops of the U-shaped channels are provided with openings 11. Through these openings are inserted U-shaped devices 12, the legs of said U-shaped devices being originally 75 straight. After insertion through the openings, however, the legs of the devices 12 are curved outwardly into almost a complete circle, as most clearly shown in Fig. 2. These ornamental borders are usually composed of long flexible strands 13, preferably 80 of twisted paper cord. These twisted paper cords in our invention are first passed in front of one leg of a U-shaped device, and thence back of the next leg of said device, 85 and so on throughout, so as to finally produce the ornamental border most clearly shown in Fig. 2.

At the corner where the U-shaped channels of the side panels meet and abut the 90 U-shaped channels of the end panels, it is desirable to preserve the rigidity of the structure in order that the said abutting channels be held together and prevented from separating. For this purpose, I provide a bolt 14 (see particularly Fig. 2) the inner end thereof being provided with a flat face 15. The round portion of the bolt is passed through the openings in the side U-shaped channel, and the outer end of said 100 round portion of the bolt is upset against the outer flange of the U-shaped channel. The said holes are so disposed that the flat plate 15 will lie against the inner flange of the upright portion of the U-shaped channel of the front panel in position to receive therethrough a screw or rivet 10. It will, therefore, be seen that by this arrangement the end panels are securely held together 105 without danger of separation or spreading. 110

If desired, braces or stiffening rods, such as 16, may be employed, preferably located on the inside of the body adjacent to the side panels. The opposite ends of these brace rods are connected, respectively, to the upper and lower U-shaped channels and the side panels.

Baby carriages are ordinarily equipped with a pivoted canopy, shaped correspondingly to the canopy disclosed in Figs. 1 and 3 of the drawing, and designated by the numeral 17, the pivots of said canopy being designated by the numerals 18—18. This canopy is composed of sides and top and a rear end panel, and is constructed in the same manner as the body portion of the carriage, *i.e.*, of woven material consisting of longitudinal warp strands, preferably of inexpensive material, such as veneer strips and transverse woof lengths, of light inexpensive material such as twisted paper cord. The sides and top of the canopy, it will be observed, are constructed from one piece of this woven material, bent and shaped to form said sides and top. The rear end panel, however, is formed of a separate piece of this woven material. The edges of the sides and top of the canopy, and also the edges of the rear panel of the canopy, are equipped with U-shaped channels, similar to the channels for the side panels and end panels of the body of the carriage, and the forward edges of the sides and top of the canopy are also preferably provided with an ornamental border composed of longitudinal strands, preferably of twisted paper cord, and woven about outstanding U-shaped devices, similar to the border provided for the body of the carriage.

The woof and warp strands, the U-shaped channels, the screws, the ornamental border, and the U-shaped holding devices for said border employed in connection with the canopy, are designated by the same reference numerals employed to designate the similar parts in the body of the carriage.

From the foregoing description of our invention, it will be seen that it embraces the use of inexpensive strips, such as veneer sheets, to form the warp strands, and inexpensive rods, such as twisted paper cord to form the woof strands.

In many forms of woven baby carriage bodies, as heretofore constructed, the side panels and end panels of the body have been made in one piece of woven material carried around corner posts so as to form the sides and ends. It is obvious that, if it were attempted to similarly form the body and employ, in the construction of the weaving, veneer sheets or strips, the latter would break and crack in being carried around such corner posts, and would not, therefore, be practical therefor. In view of this, under the old arrangement referred to, it has been

necessary to employ more expensive material, having the quality of resisting cracking and breaking. Under our invention, the carrying of the strips around corner posts is not necessary, and hence inexpensive strips can be employed. Furthermore, attention is called to the fact that under the old method referred to, the weaving had to be accomplished by hand, whereas under our invention the weaving can be accomplished by a loom, and thus a great saving of time in manufacturing is effected.

Baby carriages have also heretofore been constructed in which the side panels and end panels of the body are composed of a material woven by a loom, yet in these constructions, so far as we are aware, it has been the invariable practice to attach the woven material to wooden frames, the material being nailed to said frames.

Also, heretofore, baby carriages have been constructed wherein the sides and ends of the body are composed of wooden panels, the edges thereof being received in U-shaped channels, but in this construction the channels in no sense formed a part of the frames, but merely constituted an edge finish. The U-shaped metallic frame in our construction, however, not only constitutes a portion of the frame, but furthermore actually clenches the woven material, and thereby holds said material tight like a drum, and hence performs an entirely different function from a U-shaped channel which engaged with wooden panels.

Where the expression, "body portion" is employed in any of the claims which follow, it is to be understood that such expression is meant to include either the body portion of the carriage, or the canopy, or both.

Also, while the specification sets forth and describes the invention as adapted for baby carriages, yet it is to be understood that it is not the intention to limit the application of the novel features strictly to baby carriages, but to any form of vehicle body such as used for doll carriages, side-walk sulkies, as well as large vehicles, to which the invention may be applicable and in connection with which the invention may be useful.

What we claim as our invention is:

1. A body for carriages or the like comprising panels composed of a woven fabric, top and bottom channel iron members U-shape in cross section and securing therein the woof strands of the fabric and side channel iron members U-shape in cross section and securing therein the woof strands of the fabric, a border device carried by said channel iron members, and means engaging the channel iron members for securing the panels together.

2. A carriage or vehicle having the portion thereof which is above the lower running-gear portion, composed of a woven fab-

ric, the warp strands thereof composed of veneer strips, and the woof strands thereof of flexible twisted paper cord, and a device provided with members receiving therebetween the edges of the woven fabric.

3. A carriage or vehicle having the portion thereof which is above the running-gear portion, composed of a woven fabric, a device provided with members receiving therebetween the edges of the woven material, legs projecting from said device, and a border comprising flexible lengths passed alternately on opposite sides of the legs.

4. A carriage or vehicle having the portion thereof which is above the running-gear portion, composed of woven fabric, U-shaped frames the side members thereof receiving therebetween the edges of the woven fabric, the top or base of said U-shaped frames provided with a series of openings, a U-shaped device having the legs thereof passing

through said openings and bent outwardly, and a border comprising flexible lengths passed alternately on opposite sides of the legs.

25

5. A carriage or vehicle having the body portion proper thereof composed of side panels and end panels, each panel composed of a woven fabric, U-shaped frames for receiving the edges of the woven material of each panel, securing devices passing through the flanges of the U-shaped frames, a bolt passing through the flanges of the U-shaped frame of one panel, and having its inner end in the form of a plate resting against the inner flange of the adjacent corner U-shaped frame, and receiving therethrough one of the securing devices.

In testimony whereof we affix our signatures.

ADOLPH K. MEINECKE.
ALFRED WILD.
